UNITED STATES PATENT OFFICE

163,232

ROLL PAPER HOLDER FOR BUSINESS MACHINES

Leslie H. Taylor, Plymouth, Mich., assignor to Burroughs Adding Machine Company, Detroit, Mich., a corporation of Michigan

Application April 27, 1950, Serial No. 9,503

Term of patent 14 years

(Cl. D64—11)

To all whom it may concern:

Be it known that I, Leslie H. Taylor, a citizen of the United States, residing at Plymouth, county of Wayne, State of Michigan, have invented a new, original, and ornamental Design for Roll Paper Holder for Business Machines, of which the following is a specification, reference being had to the accompanying drawings, forming a part thereof.

In the drawings:

Figure 1 is a perspective view of a roll paper holder for business machines embodying my new design;

Fig. 2 is a side elevation thereof;

Fig. 3 is a top plan view thereof; and

Fig. 4 is an end elevation thereof.

In the drawings, a portion of a business machine, to which the novel roll paper holder is to be applied, is shown in dotted lines merely to illustrate the normal relation of the parts of

the roll paper holder to each other. The dominant features of my new design reside in the roll paper holder as shown in full lines in the drawings.

I claim:

The ornamental design for a roll paper holder for business machines, substantially as shown and described.

LESLIE H. TAYLOR.
